UNITED STATES PATENT OFFICE

2,091,137

VACUUM CLEANER

Jesse F. Carson, Cleveland, Ohio, assignor to
 Electric Vacuum Cleaner Co., Inc., Cleveland,
 Ohio, a corporation of New York

Application September 18, 1936, Serial No. 101,445

12 Claims. (Cl. 183—37)

The present invention relates to vacuum cleaners of the type in which the suction producing means and the filter are contained within an enclosing casing.

5 The object of my invention is to provide an improved construction and arrangement in cleaners of this type, and, for a consideration of what I believe to be novel and my invention, attention is directed to the accompanying description and 10 the claims appended thereto.

In the accompanying drawing, Fig. 1 is a side elevation partly in section and partly broken away of a vacuum cleaner embodying my invention; Fig. 2 is an elevation, partly broken away, 15 of the bag; Fig. 3 is a fragmentary view of the inlet end of the cleaner casing, and Fig. 4 is a sectional view showing the configuration the bag assumes around the inlet to the fan during the use of the cleaner.

20 Referring to the drawing, I have shown my invention applied to a vacuum cleaner having a cylindrical casing 1 provided with supporting wheels 2 for supporting the cleaner on the floor. Within the left end of the casing is a fan housing 25 which comprises a cup-shaped member 3 at the right end of which is fixed a cup-shaped member 4. Within the fan housing are fans 5 and 6 which are fixed to the shaft 7 of an electric motor 8. The fan 5 discharges peripherally into the 30 cup-shaped member 4, and the air flows to the inlet of fan 6 through a deflector 9 attached to the cup-shaped member 3. The fan 6 discharges peripherally to the cup-shaped member 3, and the air flows axially between the cup-shaped 35 member 3 and an annular shroud ring 10, and is discharged through an opening 11 in a cap 12 secured to the end of the casing. The shroud ring 10 extends a substantial distance along the periphery of the electric motor 8 and provides a 40 relatively unobstructed passage for the air. This decreases the friction loss, and results in improved efficiency. The electric motor is secured to an inwardly extending flange 13 on the shroud ring 10 by screws threaded into studs 14 which 45 secure the end frame 15 of the motor in place. The end frame 15 is provided with a bearing housing 16 for the motor shaft 7.

The shroud ring 10 is resiliently supported on 50 the cup-shaped member 3 by means of resilient supports each of which comprises a rubber bushing 17 clamped between a nut 18 and a sleeve 19 by a bolt 21 extending from the outside of the member 3 through the sleeve 19. The rubber bushing is provided with a reduced portion 20 55 which extends through an opening in the shroud

ring and prevents any metal to metal contact. Three or four resilient supports of this nature may be used suitably spaced around the periphery of the motor. The cup-shaped member 3 is secured to the outer casing by means of screws 22 which are threaded into the screws 21.

With this arrangement the electric motor and fan are resiliently supported by the resilient supports for shroud ring 10 and the shroud ring provided provides an annular passage for the 10 discharge of air from the fan 6. Since the motor and the rubber bushings 17 are arranged within the shroud ring the rapidly whirling air currents discharged from the fan 6 do not strike the rubber bushings at all and do not strike the motor 15 except at the streamlined rear portion, thus decreasing the friction losses. The motor is cooled by the air currents which strike its rear portion.

Due to the nature of this construction the 20 motor, fan, and fan housing can all be assembled outside the cleaner casing and inserted as a unit.

The construction described above is not my 25 invention, but is the invention of Henry T. Lang and is being claimed in his application S. N. 101,461, filed Sept. 18, 1936.

At the right end of the casing 1 is hinged a cap 23 which is provided with a suitable coupling (not shown) to which a suction hose 24 may be attached. The cap is secured to the casing by trunk latch 23a. The other end of the hose 24 30 may be attached to a suitably shaped suction nozzle. Between the cap 23 and the fan housing is arranged a cylindrical bag 25, the open end of which is secured to a supporting ring 26 by means of a clamping band 27. The supporting ring 26 35 is provided with a flange 28 which abuts the end of the casing 1 and is faced with suitable gasket material which provides an air-tight joint between the end of the casing and the cap 23. From the supporting ring 26 extend supporting 40 arms 29 which are secured at their inner ends to a ring 30 which holds the outer walls of the bag in spaced relation to the inner walls of the casing 1. The bag has a re-entrant portion 31 which fits around a tubular projection 32 projecting from the inlet 33 of the fan housing. The projecting portion 32 is provided with closely spaced 45 perforations 34 through which the air flows.

In the use of the cleaner the dust laden air flows 50 through the hose 24 into the bag 25. The air flowing through the re-entrant portion 31 of the bag causes this portion of the bag to be drawn around the member 32, as shown in Figs. 3 and 4. The irregular configuration of the bag is caused 55 by the fact that the re-entrant portion 31 is of

greater diameter than the projecting portion 32.

Due to the close spacing of the perforations 34 the bag is not drawn tightly against each perforation, so that a number of the perforations, 5 such as those indicated at 37 in Fig. 4, receive air from an area of the bag which is greater than the area of the perforations. This means that the effective filtering area of the re-entrant portion 31 is in excess of the combined area of the 10 perforations 34 but is of course somewhat less than the total area of the re-entrant portion. Some of the air flows through outer walls of the 15 bag, along the space between the walls of the bag and the cleaner casing, and to the inlet of the fan housing through perforations 35 which are 20 not covered by the re-entrant portion 31. This arrangement provides an extended surface through which the air is filtered so that the bag will hold a large amount of dirt for a given pressure drop.

When the bag is to be emptied the cap 23 is 25 swung to the open position shown in Fig. 3 and the bag is removed. The bag may then be inverted over a suitable receptacle and the re-entrant portion 31 of the bag extended to the 30 position shown in Fig. 2. A handle 38 is provided for the convenience of the operator. When in this position the operator may stand on the flange 28 of the bag, take hold of the handle 38, and shake the bag to loosen the dirt. The 35 dirt which is loosened by shaking will remain within the bag. When the bag is to be reinserted the portion 31 is pushed slightly below the ring 30 and the bag is then grasped by the supporting ring 26 and inserted into the cleaner. During this insertion the projecting member 32 pulls the re-entrant portion 31 into its proper position.

What I claim as new and desire to secure by 40 Letters Patent of the United States, is:

1. In a vacuum cleaner, a casing having an inlet for dust laden air, a fan housing, an inlet to the fan housing comprising a foraminous hollow member projecting therefrom and arranged 45 in the path of the air from the inlet to the casing, and a filter covering said projecting member and supported thereby, said filter being of substantially greater diameter than said projecting member and being flexible whereby it will be 50 drawn against said member by the air currents flowing through the filter.

2. In a vacuum cleaner, a casing having an inlet for dust laden air, a fan housing, an inlet to the fan housing including a foraminous hollow 55 member projecting therefrom and arranged in the path of the air from the inlet to the casing, and a bag between the fan housing and the inlet to the casing having outer walls spaced from the casing and having a re-entrant portion surrounding said projecting member and supported thereby.

3. In a vacuum cleaner, a casing having an inlet for dust laden air, a fan housing, an inlet to the fan housing including a foraminous hollow 65 member projecting therefrom and arranged in the path of the air from the inlet to the casing, and a bag between the fan housing and the inlet to the casing having outer walls spaced from the casing and having a re-entrant portion surrounding 70 said projecting member and supported thereby, said re-entrant portion being of substantially greater diameter than said projecting member and being flexible whereby it will be drawn against said member by the air currents flowing there- 75 through.

4. In a vacuum cleaner, a casing having an inlet for dust laden air, a fan housing having an inlet including a foraminous hollow member projecting therefrom and arranged in the path of the air from the inlet to the casing, a bag between the inlet to the casing and the inlet to the fan housing having outer walls spaced from the casing and having a re-entrant portion surrounding said projecting member, said re-entrant portion being of substantially greater diameter than said 10 projecting member and being flexible whereby it will be drawn against said member by the air currents flowing therethrough, and a frame secured to the end of the bag and extending between the re-entrant and outer walls of the bag 15 for supporting the bag.

5. In a vacuum cleaner, a casing having an inlet for dust laden air, a fan housing having an inlet including a foraminous hollow member projecting therefrom and arranged in the path of the air from the inlet to the casing, a bag between the inlet to the casing and the inlet to the fan housing having outer walls spaced from the casing and having a re-entrant portion surrounding said projecting member, said re-entrant portion being of substantially the same diameter as the outer walls of the bag and being flexible whereby it will be drawn against said projecting member by the air currents flowing therethrough, and a frame secured to the end of the bag and extending between the re-entrant and outer walls of the bag 20 for supporting the bag.

6. In a vacuum cleaner, a casing having an inlet for dust laden air, a fan housing having an inlet including a foraminous hollow member projecting therefrom and arranged in the path of the air from the inlet to the casing, and a bag between the inlet to the casing and the inlet to the fan housing having outer walls spaced from the casing and having a re-entrant portion surrounding said projecting member, said re-entrant portion being arranged and constructed to leave part of said projecting member adjacent said fan housing uncovered to provide a passage to the fan for the air flowing through the outer walls of 45 the bag.

7. In combination, a casing having an inlet for dust laden air, a hollow member arranged in the path of the air from the inlet having openings in its side walls and an opening for discharging air from the interior thereof, and a filter covering said member, said filter being of substantially greater diameter than said member and being flexible whereby it will be drawn against the side 50 walls of said member by the air currents flowing through the filter.

8. In combination, a casing having an inlet for dust laden air, a hollow member arranged in the path of the air from the inlet having openings in its side walls and an opening for discharging air from the interior thereof, and a bag between 55 said hollow member and the inlet having outer walls spaced from the casing and having a re-entrant portion surrounding said hollow member and supported thereby.

9. In combination, a casing having an inlet for dust laden air, a hollow member arranged in the path of the air from the inlet having openings in its side walls and an opening for discharging air from the interior thereof, and a bag between 60 said hollow member and the inlet having outer walls spaced from the casing and having a re-entrant portion surrounding said hollow member and supported thereby, said reentrant portion being of substantially greater diameter than said 70

hollow member and being flexible whereby it will be drawn against the side walls of said member by air currents flowing therethrough.

10. In combination, a casing having an inlet 5 for dust laden air, a hollow member arranged in the path of the air from the inlet having openings in its side walls and an opening for discharging air from the interior thereof, a bag between said hollow member and the inlet having outer walls 10 spaced from the casing and having a reentrant portion surrounding said hollow member and supported thereby, said reentrant portion being of substantially greater diameter than said hollow member and being flexible whereby it will be 15 drawn against the side walls of said member by air currents flowing therethrough, and a frame secured to the end of the bag and extending between the reentrant and outer walls of the bag for supporting the bag.
20. 11. In combination, a casing having an inlet for dust laden air, a hollow member arranged in the path of the air from the inlet having openings in its side walls and an opening for discharging air from the interior thereof, a bag between 25 the inlet and said hollow member having outer
- walls spaced from the casing and having a reentrant portion surrounding said hollow member, said reentrant portion being of substantially the same diameter as the outer walls of the bag and being flexible whereby it will be drawn against 5 the side walls of said member by the air currents flowing therethrough, and a frame secured to the end of the bag and extending between the reentrant and outer walls of the bag for supporting 10 the bag.
12. In combination, a casing having an inlet for dust laden air, a hollow member arranged in the path of the air from the inlet having openings in its side walls and an opening for discharging air from the interior thereof, and a bag between 15 the inlet to the casing and said hollow member having outer walls spaced from the casing and having a reentrant portion surrounding said member, said reentrant portion being arranged and constructed to leave part of the openings in the side walls of said member uncovered 20 to provide a passage for the air flowing through the outer walls of the bag.
